(57) CLAIM

The ornamental design for a golf club head, as shown and described.

DESCRIPTION

FIG. 1 is a toe end perspective view of a portion of a golf club head showing our new design;

FIG. 2 is a heel end perspective view thereof; and,

FIG. 3 is a side view thereof.

The broken line immediately adjacent to the shaded area represents an unclaimed boundary of the design. The broken line showing of the triangular shaped regions and the remainder of the golf club head is for illustrative purposes only and form no part of the claimed design.
